[57] CLAIM

The ornamental design for a golfer's towel having terry cloth and chamois portions, as shown and described.

DESCRIPTION

FIG. 1 is a perspective view of a towel showing a major portion of the towel composed of terry cloth type fabric and a minor portion stitched to the major portion and being composed of a chamois type material;

FIG. 2 is a top plan view of the towel of FIG. 1;

FIG. 3 is a side elevational view taken along view line 3—3 of FIG. 2;

FIG. 4 is a front edge elevational view of the towel, the rear edge being a mirror image of that shown; and,

FIG. 5 is a bottom plan view of the towel showing a stitch line at the boundary between the major and minor towel portions.
